UNITED STATES PATENT OFFICE.

PHILIP JACOB MEAHL, OF BAYONNE, NEW JERSEY, ASSIGNOR TO THE AEOLIAN COMPANY, OF NEW YORK, N. Y., A CORPORATION OF CONNECTICUT.

COMBINED PLAYER-PIANO AND PHONOGRAPH.

1,025,200.

Specification of Letters Patent.

Patented May 7, 1912.

Application filed August 14, 1911. Serial No. 643,949.

To all whom it may concern:

Be it known that I, PHILIP J. MEAHL, a citizen of the United States, and a resident of Bayonne, in the county of Hudson and State 5 of New Jersey, have invented certain new and useful Improvements in Combined Player-Pianos and Phonographs, of which the following is a specification.

This invention relates to improvements in 10 combined piano players and phonographs and the object of my invention is to provide a new and improved combined phonograph and piano player which is so constructed that the record element or perforated 15 music sheet of the piano player is automatically thrown into operative connection with its driving gear by means of a contrivance actuated at the proper time by the record element of the phonograph, all of 20 which is simple in construction, reliable and effective in use.

In the accompanying drawings in which like letters of reference indicate like parts in all the figures: Figure 1 is an elevation, 25 partly in section and partly broken away, showing parts of the music box, parts of the phonograph record, and illustrating one embodiment of my invention. Fig. 2 is a detail side view of the phonograph transmitter 30 showing the means on the same for starting the music sheet driving coupling mechanism. Fig. 3 is a face view of the transmitter showing the same parts as shown in Fig. 2.

35 The music box 1 contains the music spools 2 and 3 and tracker board 4, all of conventional construction. The shaft 5 of the lower or take-up roll 3 carries the conventional cog wheel 6 which can be engaged by 40 a barrel pinion 7 mounted on a shaft 8 which is driven in the conventional way by the motor of the player piano. When the shaft 8 is moved to the left the pinion 7 is engaged with the cog wheel 6 and the music 45 sheet is unwound from the spool 2 and drawn over the tracker board 4 and wound upon the take-up roll 3, all in the well known manner. A bellows pneumatic 9 is secured on one outer end wall of the music box 1 and 50 is provided on its movable board with the finger or arm 10 which rests against the inner end of the barrel pinion 7 so that when the bellows 9 is collapsed this finger or arm 10 moves the shaft 8 into the direction from right to left, thereby bringing

the pinion 7 into engagement with the cog wheel 6. A tube connection or conduit 11 extends from the bellows 9 to a double seating valve 12 on a stem 13 provided at its lower end with a head 14 resting on a pouch 15 over a recess 16, which valve when lowered connects the conduit 11 with the atmosphere and when raised connects the conduit 11 with a suction chamber 17, which by means of a tube or duct 18 is connected with the suction bellows or other air rarefying means. A tubular extension 19 or the phonograph horn 20 or its equivalent is swiveled in the usual way and on this free end carries a hinged diaphragm or transmitter head 21 above the disk shaped phonograph record 22 on the phonograph record support 23. The phonograph head 21 is provided with the conventional diaphragm 24 which acts upon the arm or lever 25 carrying the stylus or pin 26 in the conventional manner and of any well known construction.

A lever 27 is provided near its lower end with a cross piece 28 the ends of which are pivotally mounted in the ends 29 of a yoke 30 secured to the transmitter casing. A screw 31 is mounted in the lower end of the lever 27 and its inner end is in contact with the diaphragm transmitting lever 25 as shown. At its upper end the lever 27 carries a valve disk 32 which can seat upon and close either one of two opposite ports 33 or 34 which in the embodiment shown are formed in the inner faces of the opposite legs of a U-shaped bracket 35 projecting from the top of the yoke 30. The port 33 is connected by a duct with a passage 36 leading to the double valve 12. This duct consists of a piece of flexible tubing 37 extending to a tube 38 secured on the horn extension 19 and the opposite end of this tube 38 is connected by a flexible tubing 40 with the said passage 36. The other port 34 is connected by a flexible tubing 41 with a tube 42 also held on the horn extension 19 and the opposite end of this tube is connected by a flexible tubing 43 with the recess 16 beneath the pouch 15, the recess being provided with the suitable bleed hole 44, of any well known or suitable construction.

The screw 31 is so adjusted that in the normal position of the diaphragm in the diaphragm holder or transmitter 21 the valve 32 seats upon and closes the port 34, 110

the port 33 being open. The player piano music sheet is so adjusted that the beginnings of the slots representing the first notes of the accompaniment to be played with the 5 composition recorded on the phonograph record are slightly in advance of the ducts in the tracker, that is, only so far from the ducts so that they will be brought into speaking position as soon as the perforated 10 music sheet begins to wind upon the take-up roll. The phonograph disk or record 22 is then started and as soon as the stylus or pin 2 arrives at that part of the record line representing the musical composition to be 15 reproduced, the vibrations of the lever 25 connected with the diaphragm throw out the lower end of the lever 27 a sufficient distance to move the valve 32 from the port 34 to the port 33, as the proportions of the two arms 20 of the lever 27 are about as one to three, so that the slight movement caused by the dia- phragm at the lower end of the lever 27 moves the upper end sufficiently to throw the valve 32 from the port 34 to the port 25 33. The instant that the port 34 is opened atmospheric air rushes through the tubes 41, 42 and 43, beneath the pouch 15, where- 30 by the valve 12 is lifted and the duct 11 leading to the bellows 9 is instantly con- nected with the suction chamber 17 which causes the collapsing of the bellows 9 where- 35 by the barrel pinion 7 is thrown into en- gagement with the cog wheel 6 and rotates the take-up roll 3. It is thus clear that the 40 moment that the stylus of the phonograph is acted upon by that part of the record line representing the composition to be re- produced by the phonograph, the perforated music sheet of the piano player begins to travel.

When the valve 12 is raised the tubes 40, 38 and 37 are also connected with the suc- 45 tion chamber, and as the port 33 is closed by the valve 32 the rarefaction of air which is maintained, serves to hold the valve 32 on the port 33, and thereby holds the lower end 50 of the lever 27, carrying the screw 31 away from the diaphragm arm or lever 25 so as not to interfere with the vibrations or move- ments of the latter.

In case it is desirable to start the music sheet, for certain compositions, before the stylus of the phonograph reaches that part 55 of the record line representing the composition to be reproduced by the phonograph a few indentations or projections may be pro- vided on this line in advance of the record proper for the purpose of tripping the bracket or lever 27 before the record proper 60 of the line is reached by the stylus.

The tube 38 and tubes 37 and 40 connect- ed therewith have a diameter a trifle larger than that of the tubes 41, 42 and 43 so that when the valve 32 is seated on the port 33 65 the amount of air exhausted will be greater

than when the valve 32 seats on the port 34 so as to insure maintaining of the valve 32 seated on the port 33 while the phonograph is operated.

Having described my invention what I 70 claim as new and desire to secure by Letters Patent is:—

1. In a combined player piano and pho- nograph comprising a stylus for the pho- nograph, the combination with means for 75 moving a perforated music sheet and a mo- tor means for operating the same, of a de- vice for throwing said motor means into gear with the sheet moving means, and means controlled by the stylus of the talk- ing machine by the vibrations of said stylus for operating the device for throwing the motor into gear with the sheet moving means, substantially as set forth.

2. In a combined player piano and pho- nograph comprising a stylus for the pho- nograph, the combination with means for 85 moving the perforated music sheet and a mo- tor means for operating the same, of a bel- lows for throwing the motor means into 90 gear with the moving means, a valve mech- anism controlling the bellows and means for operating said valve mechanism from the stylus of the phonograph by the vibra- tions of said stylus, substantially as set 95 forth.

3. In a combined player piano and pho- nograph comprising a stylus for the pho- nograph, the combination with means for 100 moving the perforated music sheet, and a motor means for operating the same, of a bellows for throwing the motor means into gear with the sheet moving means, a valve mechanism for said bellows, a con- 105 trolling valve for said valve mechanism, and means for operating said controlling valve from the stylus of the phonograph, by the vibrations of said stylus, substan- tially as set forth.

4. In a combined player piano and pho- nograph comprising a stylus for the pho- nograph, the combination with means for 110 moving the perforated music sheet, and a motor means for operating the same, of a bellows for throwing the motor means into 115 gear with the sheet moving means, a valve mechanism for said bellows, a valve for controlling said valve mechanism, a lever for carrying said valve and means for op- erating said lever from the stylus of the 120 phonograph, by the vibrations of said stylus, substantially as set forth.

5. In a combined piano player and pho- nograph comprising a stylus for the pho- nograph, the combination with means for 125 moving the perforated music sheet and a motor means for operating the same, of a bellows for throwing the motor means into 130 gear with the sheet moving means, a valve mechanism for said bellows, a valve con-

trolling said valve mechanism, two independent ports at opposite sides of said valve, a lever carrying said valve, a means for actuating said lever from the stylus of the phonograph and connections between said ports and valve mechanism of the bellows, substantially as set forth.

6. In a combined piano player and phonograph comprising a stylus for the phonograph, the combination with means for moving the perforated music sheet, and a motor means for operating the same, of a bellows for throwing the motor means into gear with the sheet moving means, a valve for the same, a valve controlling said valve mechanism, two independent ports at opposite sides of said valve, a lever carrying said valve, a means for actuating said lever from the stylus of the phonograph, connections between said ports and the valve mechanism of the bellows, and a screw for the adjustment of said lever, substantially as set forth.

7. In a combined piano player and phonograph comprising a stylus for the phonograph, the combination with means for moving the perforated music sheet, and a motor means for operating the same, of a bellows for throwing the motor means into

gear with the sheet moving means, a valve for controlling the exhaustion of air from said bellows, a pouch for operating said valve, a conduit extending from said pouch to a port, a valve for said port, a lever carrying said valve, means for operating said lever from the stylus of the phonograph, an additional port facing said valve, and a tube connection extending from said port to the valve mechanism for the bellows, substantially as set forth.

8. In a combined piano player and phonograph comprising a stylus for the phonograph, the combination with means for moving the perforated music sheet and a motor means for operating the same, of a device for throwing the motor means into gear with the sheet moving means, which device is operated by the vibrations of the phonograph stylus, substantially as set forth.

Signed at New York city, in the county of New York, and State of New York, this 7th day of August A. D. 1911.
